HANGER

Robert F. Teders, Freeport, Ill.

Application June 26, 1936, Serial No. 87,573

3 Claims. (Cl. 211—87)

This invention appertains to new and useful improvements in a support, and more particularly to a novel form of pants hanger.

The principal object of the present invention is to provide hanger means for pants whereby pants can be hung by the belt loops in a manner which will eliminate or prevent the marks usually noticeable which now occur in the use of conventional hangers when the trousers are hung over a bar at the knees or by a clamp at the cuffs.

Another important object of the invention is to provide a hanger which is adjustable to different size pants and which in use will not be susceptible to the ready development of defects.

Further objects of the invention are to provide a hanger from which trousers can be removed selectively without affecting the position of others on the hanger and a hanger which is constructed in such a manner that it can be secured to the inside of a closet door, thus utilizing space which is normally not utilized.

An additional valuable feature is that trousers can be hung on this hanger without removing objects from the pockets thereof.

These and various other important objects and advantages of the invention will become apparent to the reader of the following specification.

In the drawings:

Figure 1 represents a front elevational view of the entire hanger.

Figure 2 is a top plan view of the hanger.

Figure 3 is a sectional view taken substantially on the line 3—3 of Figure 1.

Figure 4 is a sectional view substantially on line 4—4 of Figure 1.

Figure 5 is a fragmentary top plan view of one of the arms.

Referring to the drawings wherein like numerals designate like parts, it will be seen that numeral 5 represents an elongated L-shaped and horizontally disposed wall member which is provided with side and end walls 6 which space the front away from the supporting wall 7. The depending portion A of the wall member 5 is provided with three short horizontally disposed slots 8, while the distant end of the horizontal portion b of the member 5 is provided with elongated slots 9—10. Suitable screws or the like 11 are disposed through the ends of the member 5.

For supporting pants by their belt loops, arm structures generally referred to by numerals 12—13 are employed. The arm structure 13 consists of the elongated member 14 provided with hook members 15 depending therefrom at equal

longitudinally spaced intervals. One end of the elongated member 14 is turned up as at 16, while its opposite end is provided with a depending plate formation 17 also having a hook 15 thereon. The plate formation 17 is provided with lateral and apertured ears 18 and at its upper portion is provided with a longitudinal offset and upwardly extending lug 19 for engagement against the back side of the member 5, after it has been inserted through one of the slots 8. With the lug 19 engaged with the plate 5 in this manner and the plate formation 17 being resting against the front of the member 5, the arm 13 is supported in the horizontal position suggested in Figure 4.

The arm 12 is constructed in substantially the same manner, the same having a lug 19a which is engaged with the back side of the plate 5 after having been disposed through slot 9.

As suggested in Figure 1 by broken lines, the trousers are hung up by disposing the belt loop in the center on the back of the trousers over a hook member 15 on arm 12 and the two belt loops on the front of the trousers and in line with the front creases in the legs of the trousers over members 15 on arm 13. The arm 12 can be adjusted to any extent desired depending upon the waist measurement of the pants.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A hanger for hanging pants by their belt loops comprising an elongated horizontal member having a depending leg at one end thereof, said leg having a plurality of vertically spaced openings therein, a hanger member having a lug disposed through one of the openings for holding the hanger member to the leg, and a hanger member mounted on the opposite end of the horizontal member, and a lug and slot connection between the last-mentioned hanger member and the horizontal member whereby the hanger member can be adjusted longitudinally on the horizontal member.

2. A hanger for hanging pants by their belt loops comprising an elongated horizontal member having a depending leg at one end thereof, said leg having a plurality of vertically spaced openings therein, a hanger member having a lug disposed through one of the openings for holding

- the hanger member to the leg, and a hanger member mounted on the opposite end of the horizontal member, and a lug and slot connection between the last-mentioned hanger member and the horizontal member whereby the hanger member can be adjusted longitudinally on the horizontal member, and securing means between the last-mentioned hanger member and the horizontal member whereby the hanger member can be secured in any desired position along its lug and slot connection to the horizontal member.
3. A hanger for hanging pants by their belt loops comprising an elongated horizontal member having a depending leg at one end thereof, said

leg having a plurality of vertically spaced openings therein, a hanger member having a lug disposed through one of the openings for holding the hanger member to the leg, and a hanger member mounted on the opposite end of the horizontal member, and a lug and slot connection between the last-mentioned hanger member and the horizontal member whereby the hanger member can be adjusted longitudinally on the horizontal member, said elongated horizontal member and leg being of channeled construction into which the said lug can project. 5 10
